UNITED STATES PATENT OFFICE.

DANIEL H. MCKINNON, OF MOORETOWN, ONTARIO, CANADA.

TLTING BARREL-SUPPORT.

SPECIFICATION forming part of Letters Patent No. 394,931, dated December 18, 1888.

Application filed May 28, 1888. Serial No. 275,373. (No model.)

To all whom it may concern:

Be it known that I, DANIEL H. MCKINNON, a citizen of the Dominion of Canada, residing at Mooretown, in the county of Lambton and Province of Ontario, Canada, have invented 5 certain new and useful Improvements in Tilting Barrel-Supports, of which the following is a specification, reference being had therein to the accompanying drawings.

10 This invention relates to certain new and useful improvements in tilting-trucks designed for supporting barrels under counters for their easy and convenient use in retailing sugar and other like articles preferably 15 sold out of the barrel.

The invention consists in the peculiar combinations and the construction, arrangement, and adaptation of parts, all as more fully hereinafter described and claimed.

20 In the drawings which accompany this specification, Figure 1 is a vertical central section of my improved tilting-truck supporting a barrel in vertical position. Fig. 2 is a top plan of the truck. Fig. 3 is a bottom plan thereof. Fig. 4 is a cross-section similar to Fig. 1, but showing the truck in its tilted position. Fig. 5 is a side elevation of the truck. Fig. 6 is a longitudinal section on line 25 *x x* in Fig. 2.

30 A are the sides, and B a central cross-bar connecting the two sides to form a rigid frame, in which are journaled the shafts C, which carry the rollers D, the whole constituting a truck adapted to support a barrel so that it 35 will rest with its bottom on top of the rollers, as shown in Fig. 1.

E E are two brake-shoes, connected by a central longitudinal bar, F, to form a sliding frame having a limited play in relation to the 40 truck, so that by sliding said frame longitudinally toward one end or toward the other one of the two brake-shoes is brought in frictional contact with one pair of rollers.

G is a sliding bar longitudinally supported 45 upon the shaft C between the rollers, and this sliding bar passes loosely through suitable slots, H, in the brake-shoes, thereby supporting the latter and guiding them in their operation, the bar G being itself guided by the 50 inner sides of the rollers, which prevent it from lateral displacement. The upper face of the sliding bar G is in a plane below the

top of the rollers, and to its center it has secured a bearing-block, I, the upper face of which is on about the same plane as the top 55 of the roller, and the screw J passes through its center from underneath, suitable holes, K, being provided through the cross-brace B and longitudinal sliding bar F to permit the insertion of the screw-driver from underneath 60 to actuate the screw J.

The stand may be so arranged with reference to the counter that when the stand is tilted to an upright position from its forwardly-tilted position and moved under the 65 counter the barrel will strike the counter before the truck can tilt rearwardly; or the stand may be so arranged with reference to the counter that it can tilt rearwardly before the barrel strikes the counter, and thus raise 70 the forward end of the truck out of the way of the feet of the salesman. Fig. 1 shows the first of these arrangements, and Fig. 4 the second.

In practice, the parts being arranged and 75 constructed as described, the truck is secured in the center of the bottom of a barrel by means of the screw J, as shown in Fig. 1. This is easily accomplished by tipping over the barrel on its side and attaching the truck 80 to it while in this position, the truck being comparatively small and light. In righting the barrel again the whole weight of it rests upon the top of the rollers D, and the sliding bar G impinges with its ends, or nearly so, 85 against the chine of the barrel. Now, it will readily be seen that if from this normal position of supporting the barrel (at which the center of the barrel falls directly over the center of the truck) the barrel should be 90 pushed one way or the other a displacement of the center of the barrel will take place relative to the center of the truck; but this displacement is limited by the block I, which strikes against one of the two brake-shoes E, 95

and thereby causes the other brake-shoe to draw in frictional contact with one pair of rollers. Now, since the wheels of the truck are braked and kept from any forward motion, any further power applied to the barrel 100 causes it to tilt, as shown in Fig. 4. By pushing the barrel in the reverse direction it will return to its upright position first, and then the bearing-block I, striking against the op-

posite brake-shoe, causes the same stoppage in the travel of the barrel and a tilt in the reverse direction.

Placing the barrel under the counter, the forward withdrawal of the barrel will cause it first to move from under the counter, and then to tilt forwardly sufficiently to gain access to the contents. In the rearward movement of the barrel it will first move under the counter, and then it will tip rearwardly, and thereby raise the lower front edge of the barrel with the truck off the floor to be out of the way of the feet of the operator. Fig. 1 represents the same after the first movement before the barrel is tipped rearwardly, and Fig. 4 shows the same tilted rearwardly. Instead of having the bearing-block I actuate the brake-shoes, it is obvious that the chine of the barrel in striking against one of the brake-shoes will accomplish the same object.

The sliding bar G is the means for adjusting the truck on the barrel and to prevent accidental displacement. The brake device makes the operation of the truck more positive.

What I claim as my invention is—

1. In a truck for supporting barrels under counters, the combination, with the frame and

the wheels or rollers journaled therein, of the bar G, longitudinally movable on said frame 30 and of sufficient length to fit between and engage the chine of a barrel, substantially as described.

2. In a truck for supporting barrels under counters, the combination, with the frame and 35 the rollers journaled therein, of the bar G, slidably secured on said frame, and the bearing-block I, secured to said bar, substantially as and for the purpose specified.

3. In a truck for supporting barrels under 40 counters, the combination, with the frame, of the shafts C, journaled therein, the rollers D, arranged in pairs, the sliding bar G, supported between the rollers and provided with the bearing I and means for securing it to the 45 barrel, and the brake-shoes E, slidably connected and carried by the truck-frame, all arranged to operate substantially as described.

In testimony whereof I affix my signature, in presence of two witnesses, this 1st day of May, 50 1888.

DANIEL H. MCKINNON.
